(57) **CLAIM**

The ornamental design for a video conferencing device, as shown and described.

DESCRIPTION

FIG. 1 is a top, left side perspective view of the video conferencing device showing our new design;

FIG. 2 is a top, right side perspective view thereof;

FIG. 3 is a bottom perspective view thereof;

FIG. 4 is a rear perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof; and,

FIG. 10 is a right side elevation view thereof.

The broken lines depict portions of the video conferencing device that form no part of the claimed design.
